UNITED STATES PATENT OFFICE.

JOSEPH B. CLAY, OF CEDAR FALLS, IOWA.

STANCHION.

1,355,538.

Specification of Letters Patent. Patented Oct. 12, 1920.

Application filed November 16, 1917. Serial No. 202,279.

To all whom it may concern:

Be it known that I, JOSEPH B. CLAY, a citizen of the United States, residing at Cedar Falls, in the county of Blackhawk and State of Iowa, have invented certain new and useful Improvements in Stanchions, of which the following is a description.

My invention belongs to that general class of devices known as stanchions and refers particularly to a stanchion for use in connection with bull pens and the like. The invention has among its objects the production of a device of the kind described that is simple, strong, rigid, durable, efficient, attractive and satisfactory for use wherever found applicable. Many other objects and advantages of the construction herein shown and described will be obvious to those skilled in the art from the disclosure herein given.

To this end my invention consists in the novel construction, arrangement and combination of parts herein shown and described, and more particularly pointed out in the claim.

In the drawings, wherein like reference characters indicate like or corresponding parts,

Figure 1 is a view in elevation, with a portion broken away, of my improved device and a portion of the pen;

Fig. 2 is a sectional view taken substantially on line 2—2 of Fig. 1;

Fig. 3 is a sectional view taken substantially on line 3—3 of Fig. 1;

Fig. 4 is a sectional view taken substantially on line 4—4 of Fig. 1; and

Fig. 5 is a sectional view taken substantially on line 5—5 of Fig. 1.

Referring to the drawings in which the preferred form of the device is shown, 1 represents the curb or floor, 2—2, etc., uprights or bars constituting the walls or sides of the pen, and 3—3 the top rail, or the equivalents, suitably carried thereby. I have not considered it necessary to illustrate the complete pen nor all of the details thereof. The stanchion may be arranged where desired, and the height and width or distance between the uprights 2—2, between which the stanchion is to be located, is as preferred by the user of the stanchion. In constructing a new pen, where uprights and a top rail are employed, the upper or top rail 3 is extended beyond the uprights 2 as indicated at 4, and when the same is

applied to a pen of similar type already constructed, a section of the top rail is cut out and the intermediate upright or uprights removed. Spanning the space between the ends of the top rail, or its equivalent, and carried thereby, is a head bar 5 which is preferably channel or U-shaped with the open side at the bottom. The bar 5 is secured to the ends of the rails 3—3, or the equivalent, by the desired number of bolts 6 or their equivalents for the purpose.

Arranged between the uprights 2—2 with the lower ends suitably anchored at the floor or curb are the stanchion members 7—7. In the construction shown, I form the lower ends of the stanchion members 7—7 with the ends 8 and pivotally secure the same by means of bolts 9, or the equivalent, to a base plate 10. The base plate is suitably braced and provided with depending parts 11, which may be headed as at 12, the parts 11 and 12 being embedded in the floor or curb, which is ordinarily of concrete or the like. This affords a very rigid and secure construction and has the advantage of being sanitary as well as attractive. It will be noted that I provide a plurality of holes in the base plate 10 through which the bolts 9 may be passed so that the width of the stanchion at the bottom may be varied and made to conform to the size of the animal or stock held.

The stanchion members 7—7 are of a length so that the same project into the head bar 5. The same are cut at an angle at the end as at 15, or slotted on one side so as to clear the latch member when in its raised position and the stanchions are moved to closed positions. In the case illustrated, I provide two latch members, one for each stanchion, each consisting of the part 16 arranged at the end to engage the end of the stanchion bar, and as at 19 to afford a handle for operating or controlling the same. As shown, the latches are pivotally secured to the head bar by bolts 17 or their equivalents, and it may be mentioned that the latches are so constructed that they normally always hang in operative engaging position, the end being beveled so that the stanchion may be closed and automatically raise and then engage with the latch without requiring the touching of the handle part 19. I also provide a plurality of holes 18 through which the bolts 17 may be passed so that the positions of the latches

may be varied or adjusted, and the width or distance between the stanchion bars be thereby varied at the top. The latches are preferably constructed so that the handle portions are flush with the top face of the bar when the latches are in operative positions. They are prevented from dropping to an inoperative engaging position by the lugs 16', which are arranged to engage the under face of the bar.

As before mentioned, the stanchion device herein illustrated is not only applicable in its essentials for new work, but may be applied to practically any type of the pens in use. By making the handles 19 substantially flush with the top of the head bar 5, the same is not easily operated by the animal and the same thereby be accidentally released. The animal is securely locked in place at such times as may be desired, for example, during the feeding, cleaning the stall or pen, or other times. The stanchion harmonizes with the other part of the pen and is therefore attractive.

Having thus described my invention, it is obvious that various immaterial modifications may be made in the same without departing from the spirit of my invention, hence I do not wish to be understood as limiting myself to the exact form, construction, arrangement and combination of parts

herein shown and described or uses mentioned.

What I claim as new and desire to secure by Letters Patent is:—

In a bull pen stanchion of the kind described and in combination, an inverted U-shaped bar slotted on the top thereof, means for securing the same to the adjacent top rails of the pen, a pair of coöperating tubular stanchion bars, means for anchoring said bars at their lower ends comprising a base plate, means for securing said base plate in place, means for securing the lower ends of said stanchion bars to the plate, said stanchion bars at their upper ends extended into the U-shaped head bar and movable therein, and a plurality of latch members pivotally mounted within the head bar and operable through said slot in the top thereof, said latch members arranged to limit the closing movement of the bars and engage the upper ends of said stanchion bars on the interior and lock the same in closed position.

In testimony whereof I have hereunto signed my name in the presence of two subscribing witnesses.

JOSEPH B. CLAY.
